ELECTRIC SWITCH

Montford Morrison, Montclair, N. J., assignor to
Westinghouse Lamp Company, a corporation
of Pennsylvania

Application March 5, 1932, Serial No. 596,948

4 Claims. (Cl. 250—27.5)

This invention relates to electrical switches and more particularly to switches of the character adapted to "make" and "break" an electrical circuit of predetermined voltage and current values.

- 5 In its more specific aspect the invention is directed to a thermionic switching or trigger device adapted to operate without detrimental arcing in an electrical circuit where the voltage applied to the thermionic device is of the order of about 10 forty thousand volts or more and the current passing through said device may be about one thousand milliamperes more or less.

In some of the electrical commercial arts it is sometimes essential that electrical energy of 15 predetermined voltage and current characteristics be applied to a pair of conductors for a predetermined length of time. One of the fields where the above factors are of importance is the X-ray photographic field where "instantaneous" exposure radiographic plates are desired. 20 These so-called "instantaneous" exposure radiographic plates may be prepared by subjecting the object to be X-rayed to a beam of X-radiation of appropriate intensity and wave lengths for a 25 limited period of time, which is of the order of a fraction of a second.

In order that an "instantaneous" exposure X-ray plate or film may be produced in such a short period of time, it is essential that the wave 30 lengths of the X-radiation of the X-ray beam and the intensity of the X-ray beam directed on the object to be X-rayed be of at least certain magnitudes so that the plate or film may receive and be properly affected by a comparatively large 35 quantity of X-rays of selective wave lengths.

In the course of my experimentations with X-ray tubes in general in the radiographic art, I have observed that good X-ray photographic plates of the "instantaneous" exposure type may 40 be produced providing the electrical energy supplied to an X-ray tube has certain characteristics. Some of the salient characteristics of the electrical energy employed for this purpose which must be taken into consideration are, the magnitude 45 of the applied tube voltage, the time duration of said applied tube voltage, and the magnitude of the tube current. To obtain good "instantaneous" exposure radiographic plates I have found that the time of X-ray exposure should 50 be very short and of the order of a small fraction of a second, both the applied tube voltage and the tube current should be relatively high and of the order of about forty thousand volts and upward and about one thousand milli- 55 amperes more or less respectively, the latter of

which is an exceedingly high tube current for X-ray work. By virtue of the employment of this type of electrical energy, the intensity and wave lengths of the X-ray beam produced are of sufficient magnitude to permit the production of a 5 superior "instantaneous" X-ray plate in a small fraction of a second.

Briefly stated, my invention comprises a three electrode tube which is adapted to prevent and allow the "instantaneous" discharge of a condenser at a high potential after it is charged. 10 The tube consists primarily of a gas-tight dielectric envelope having an anode and a cathode appropriately spaced from each other and a grid of novel design appropriately spaced between 15 the cathode and the anode. With a tube of this general construction embodying my invention, it is practical to block the discharge of a charged condenser for a period of time and at an appointed time to allow the discharge of said condenser therethrough, which discharge may be as 20 high as one thousand milliamperes or more at forty thousand volts or upward.

One of the objects of my invention is to provide means whereby electrical energy of high voltage values may be applied to an X-ray tube for a relatively short period of time, without detrimental arcing or current discharge. 25

Another object of my invention is to provide 30 a thermionic tube capable of effectively preventing and allowing the "instantaneous" passage therethrough of electric energy which is of comparatively high potential and high current values for X-ray use.

Another object of my invention is to provide 35 a new method of preventing and allowing the passage of electrical energy from a source of electrical supply to a load.

Another object of my invention is to provide 40 a new method of preventing and allowing the passage of electrical energy of high voltage and high current values from a source of electrical supply to a load.

Another object of my invention is to provide 45 a new method of preventing and allowing the "instantaneous" passage of electrical energy from a source of electrical supply to a load.

Other objects and advantages of my invention 50 will be readily apparent from the following specification and appended drawings wherein,

Figure 1 represents a shortened longitudinal cross sectional view, with some of the parts in elevation of a device embodying my invention;

Figure 2 represents a cross sectional view taken 55

along line II—II of Figure 1 in the direction of the arrows;

Figure 3 represents a cross sectional view taken along line III—III of Figure 1 in the direction of the arrows;

Figure 4 represents a modification of Figure 3;

Figure 5 represents a cross sectional view along line IV—IV of Figure 4.

As shown in Figure 1, one embodiment of my invention is the illustrated trigger tube A comprising an evacuated enclosing gas tight dielectric elongated envelope 10, composed of glass or the like, in the form of a bulbous mid-portion 11 with a pair of diametrically opposed elongated 15 tubular arms 12 and 13. Extending within said tubular arms 12 and 13 respectively, are a plurality of reentrant dielectric tubes 14 and 15 having presses 16 and 17 at their respective ends, located in proximity of the respective limits of the 20 bulbous portion 11. Located within the envelope 10 and with the effective portions thereof in the approximate center of the bulbous portion of the envelope are a plurality of spaced parallelly arranged electrodes 18, 19 and 20. The pressure 25 of the residual gas within the tube is preferably as low as possible and may be of the order of about 10^{-5} to 10^{-4} mm. of mercury.

The electrode 18 is the plate or anode in the form of a plane smooth surface disc, having the 30 circumferential outer portion thereof curled upwardly and inwardly towards the anode end of the envelope, and away from the electrodes 19 and 20 to provide a surface of large radii of curvature so as to minimize cold electron emission 35 between the electrodes.

This anode or plate 18 may be about 25 mils thick and composed of a refractory metal, as for example, molybdenum and is supported by an electrical conductor 21 of molybdenum or the 40 like having one end secured thereto and its outer end secured to the conductor 22. The effective anode area is preferably greater and about fifty percent greater than the overall area of the cathode 20, hereinafter more specifically described. Between the anode or plate 18 and the conductor 22, a portion of the supporting conductor 21 forms an air-tight seal and supporting means with the vitreous press 16. Secured to a 45 face of the anode or plate 18, within the periphery of the curled edge thereof by means of welded right angle supports or other mechanical means, is a metallic tubular section 23 composed of molybdenum or the like.

This tubular section 23 extends away from the effective anode 18, surrounds that portion of the anode support and conductor 21 within the envelope, the seal and press 16, and a substantial portion of the reentrant tube 14 beyond the press. 50 On the inner surface of that portion of the tube 23 surrounding the reentrant tube are secured a plurality of spring fingers 24 whose outer surfaces bear against the outer surface of the reentrant tube 14. This metallic tubular section 55 23, due to this peculiar assembly and design, serves as a heat distributor and a shock-absorbing and distributing means to aid in the prevention of anode over-heating, seal impairment due to heat and/or stray electron bombardment 60 thereof and seal fracture.

Moreover this particular construction aids in the prevention of general tube fracture caused by mechanical shocks to which tubes of this character might normally be subjected in the course 65 of practical commercial manufacture, manipula-

tion or operation. It also serves to assist in supporting the anode 18.

At the cathode side of the tube and forming an air-tight seal with the press 17 are a plurality of cathode lead-in and rigid supporting wires 25 and 26 having portions thereof extending exteriorly of the envelope and portions thereof extending within said envelope. Substantial lengths of the upper free ends 27 and 28 of the support wires 25 and 26 are bent outwardly and 10 away from each other and are at about right angles to the longitudinal axis of the tube. Between said supporting wires and sealed in the press 17 are a plurality of, and as illustrated six, rigid supporting wires 29, 30, 31, 32, 33 and 34 15 composed of molybdenum or the like, and insulated from each other at the press 17. The upper portions of these wires are bent away from the longitudinal axis of the tube, with upper portions of the wires 29, 30 and 31 bent in a direction generally opposite to the direction of bend of the wires 32, 33 and 34.

The free ends of these wires are all approximately in the same general plane, which is substantially normal to the longitudinal axis of the 25 envelope. Securely mounted by welding or other convenient means to the bent portions at or near the free ends thereof, in a generally zig-zag fashion as shown with each of its segments being in the same general approximate plane, is the 30 filamentary cathode 20.

The cathode 20 may comprise a tungsten filament measuring about 20 cms. in length and 16.5 mils in diameter and has its respective ends secured to the bent portions 27 and 28 of the support wires 25 and 26. Because of such composition, length and diameter, the cathode 20 will provide a thermionic emission therefrom, of sufficient magnitude to supply the desired comparatively large current of the order of about 1000 40 milliamperes, when a potential of about seventeen volts is applied between its terminals from the secondary winding of a low voltage transformer connected to lead in wires 25 and 26. Moreover, this comparatively large thermionic 45 electron emission is effectively secured at the temperature to which the filament is raised without any substantial vaporization thereof at its maximum attained temperature due to said voltage being applied between its terminals. 50

Spaced from and closely surrounding the thermionic cathode 20 is an open ended cup 36 of molybdenum or the like, having an inwardly directed flange with a downwardly extending cylindrical portion integral with said flange and 55 having a curled upper end whose edge is away from the face of the anode 18 and in close proximity to the outer surface of the cup proper.

The cup 36 has a base 37 provided with an elongated slot 38 adapted to receive the rigid 60 support wire 26 and the support wires 29, 30, 31, 32, 33 and 34. The other rigid support wire 25 passes through and is in contact with the base as shown in Figure 2. The support wire 25 may be welded to said base, although this is not necessary because it is sufficiently in contact therewith as shown in Figure 2.

The inner wall of the cup 36 is in close proximity of the ends of the bent support portions. Its upper curled edge is above the plane of the 70 cathode and the flange portion extends inwardly and below the edges of the bent portions of the support and together with its base serves as a reflecting surface for the electrons emitted at the cathode 20. Telescoping the downwardly extend- 75

ing cylindrical portion integral with said flange is a metallic tubular section 40 having one end thereof secured to said cylindrical portion. This tubular section 40, composed of molybdenum or the like, supports the cup, surrounds all of the cathode supporting wires, the press and a substantial portion of the reentrant tube beyond the press.

On that portion of the inner wall of the tubular section 40, surrounding the reentrant tube 15, are secured a plurality of spring fingers 35 adapted to frictionally engage and bear against the reentrant tube 15.

The cup 36, together with the cylindrical section 40, serves as a heat distributor and a shock absorbing and distributing means to aid in a prevention of seal impairment due to heat and/or stray electron bombardment thereof which may ultimately result in seal break down. Moreover, this particular construction aids in the prevention of tube fracture caused by mechanical shocks to which a tube of this character might normally be subjected in the course of practical commercial manufacture, manipulation or operation. It also serves to prevent the electrons emitted at the cathode from migrating over towards the walls of the envelope and acts to constrain the electrons in a limited field so that they may approach the anode in a preferred path upon excursion.

At the respective ends of the vitreous bulb 10 are secured terminal caps 43 and 44 in electrical contact with the respective lead in wires 22 and 25, 26. The vitreous envelope 10 is of appropriate length so that these caps 43 and 44 are remotely disposed from each other to prevent spark over therebetween when a potential of forty thousand volts or more is applied therebetween.

Integral with the envelope 10 at about the mid-length thereof and the bulbous portion 11 is a relatively short outwardly extending vitreous cup 38 having a relatively short reentrant tube 39 forming an air tight seal. Within said reentrant tube 39 is a Y supporting molybdenum member 41 secured to the third electrode 19 and sealed in the tube 39. The third electrode 19 is essentially a control electrode and, as shown in Figures 1 and 3, may comprise a metallic cup whose internal diameter is substantially greater than the corresponding external dimension of the cup 36.

The cup shaped control electrode 19 is of substantial depth and may have a perforated base 42 with the edge of the perforations being preferably rounded to prevent cold electron emission. The distances between the perforations are preferably less than the corresponding dimension of said opening. The control or grid electrode 19, supported by the lead 41, is located between the anode 18 and the cathode cup 36 with its sides surrounding the upper portion of the cup 36, extending downwardly appreciably below the upper edge of said cup 36 and appropriately spaced therefrom.

The perforated base of the cup is preferably disposed substantially parallel to the planes of the anode and cathode, with the virtual longitudinal center line of the envelope passing through the approximate centers of the planes of each of the electrodes 18, 19 and 20.

Closely adjacent the seal of the arm 41 and the reentrant tube 39 is a cup shaped member 43 of molybdenum or the like secured to said arm and shielding said seal from electron bombardment or radiated heat. In order that this novel tube may be operable in a circuit so as to efficiently and effectively prevent and allow the instantaneous discharge therethrough of electric energy

having high potential and high current characteristics in the X-ray field consideration must be given to the composition and size of each electrode, as well as to the relative positions of these electrodes to each other.

The anode and cathode are preferably so spaced from each other that any danger of filament distortion or other deleterious effects, such as arcing, may be prevented during the operation of the tube at the high voltages to which it may be normally subjected.

The cup-shaped grid 19 surrounding the cup 36 has its bottom 42 substantially parallel to each of said electrodes and is adapted when negatively biased to prevent electron flow from said cathode to said anode when said cathode is at operable temperatures. Thus, a zero plate current may be maintained when the cathode is heated to its maximum temperature and a high voltage is applied between the anode and the cathode terminals because the sides of the control electrode 19, together with the cup 36, which is electrically connected to and at approximately the same potential as the cathode 20, acts as a mechanical and electrical barrier to prevent the electrons from migrating outside of the sphere defined by the cup 36 and the control electrode 19.

Besides being amenable to said shielding or blocking action the grid is preferably of such composition and design that when it is positively biased it will instantaneously allow and aid the migration of electrons from the cathode to the anode to provide a high value plate current of the order of about 1000 milliamperes.

The control electrode 19 may be of any suitable design, as for example, as shown in Figures 1 and 2, merely set forth as illustrative embodiments. As illustrated in Figures 1 and 2 the control electrode 19 may comprise a cup-shaped member having an overall area substantially greater than that of the cathode and about equal to that of the anode, and so positioned in the envelope that its sides may extend downwardly below the upper limit of the cup 36 and spaced from the sides thereof. By the term "overall area" of the cathode I mean the area of a plane whose perimeter is defined by the outermost points of the filament.

The base of the cup located between the anode and the cathode is preferentially perforated so as to allow upon discharge the migration of a large number of electrons from the cathode to the anode to provide a large value plate current in the X-ray art without undue overheating of the grid. Further the size and spacing of adjacent perforations are of such a magnitude that a comparatively low negative potential may be applied to said grid to provide an electrostatic field sufficient to prevent, when the cathode is at its maximum temperature, the establishment of a continuous electrostatic field and an electron flow between the active surfaces of the cathode and the anode.

Although any refractory material, such as tungsten or tantalum, may be employed as a control electrode material, I prefer to employ molybdenum for this purpose because of its electrical and mechanical characteristics and especially its relatively high secondary electron emission property. By employing an appropriately dimensioned grid of molybdenum, having its base perforated over an area equal to that of the anode or cathode, in a tube of this character adapted to discharge a relatively high current for X-ray use of the order of about 1000 milli-

amperes at a relatively high voltage, the grid does not become unduly overheated and the grid current value during discharge is moderately low.

- 5 The control electrode 19, of predetermined composition and design, is so positioned between the anode 18 and the cathode 20 that when a high potential is applied between the cathode and the anode terminals and the grid having 10 a negative bias sufficient to prevent electron flow from the active cathode to the anode, the intensity of the electrostatic field between the cathode 20, the cup 36 and the grid 19 will be insufficient to cause any substantial distortion 15 of either the rigid grid 19 or the cathode 20. The grid 19 is also so spaced from the anode that there is no appreciable sparking therebetween and the electrostatic field is insufficient to cause distortion of either or both of the component parts. The spacing of the grid 19 from the 20 anode is important because if the spacing is not great enough, the potential gradient at the surface of the grid during the blocking action when the cathode is incandescent may be so high 25 that cold emission or sparking takes place. If there is appreciable cold emission or sparking at the grid, the blocking action of the grid is obviated and the current will flow from the cathode to the anode at some time other than that appointed.

Another type of grid or control electrode that I have found suitable for my purposes is illustrated in Figures 4 and 5 and comprises essentially a molybdenum wire mesh cup 45 of approximately 30 the same general dimensions as the cup 19.

The openings in this screen and the spacing between each opening are preferably of the same approximate dimensions as the corresponding dimensions of the corresponding parts of the base 40 42. Surrounding the sides and lower edge of said foraminous cup and extending up to the base thereof is a substantially cylindrical thin sheet of molybdenum 46 of a U cross section.

It has been found that tubes embodying my 45 invention and having electrical energy of high voltage, of the order of about sixty thousand volts between the terminals of the anode 18 and the hot cathode 20, may be completely prevented from discharging between these electrodes 50 by virtue of the grid or control electrode 19 having a negative grid bias of about three thousand volts.

This tube also by virtue of its particular construction besides being able to prevent the passage therethrough of said electrical energy will 55 by proper means allow the "instantaneous" passage of high currents of the order of about one thousand milliamperes at a voltage of about sixty thousand volts without any arcing or high power losses.

With the tube construction herein described a 1000 volt positive grid bias may be substituted for the 3000 volt negative grid bias so that the tube will allow the instantaneous passage therethrough of electrical energy of the order of about 60 sixty thousand volts and one thousand milliamperes, without any fusion or undue overheating of the electrodes.

Although I have described one of the forms 70 of my invention with minute particularity I do not wish to be limited thereby because it is sus-

ceptible to a number of modifications and is to be limited only by the prior art.

What is claimed is:

1. A switch for effectively preventing the flow of current therethrough and allowing at an appointed time the passage of electrical energy therethrough, comprising an envelope, an anode, a thermionic cathode, a control electrode, and means surrounding said cathode for limiting the direction of movement of the electrons emanating from said cathode when said cathode is heated, said means having a portion thereof located beyond a limit of said cathode, said means being electrically connected to said cathode, a portion of said control electrode being adjacent a portion of said means for the establishment of an electric field when a potential is applied between said means and said control electrode to prevent electrons emanating at the cathode from passing between the space defined by said portions of said means and said control electrode, said control electrode having openings therein and being cup-shaped, the concave side of said control electrode surrounding said means, with the side of said cup being opposite the side of said means along an appreciable length of said means.

2. An electric switch for effectively preventing the flow of current therethrough and allowing the flow of electrical energy comprising an envelope, an anode, a thermionic cathode and a control electrode therein, means for limiting the direction of movement of electrons emanating from said cathode when said cathode is heated, said means having a mouth facing said anode, said cathode being located in said means and below the upper limit of the mouth thereof, said control electrode surrounding the mouth of said means and having a portion thereof extending outside and below the mouth of said means, said portion being spaced from a portion of said means.

3. A switch for effectively preventing and allowing the passage therethrough of electrical energy comprising an envelope, a plurality of presses therein, conductors sealed in said presses, an anode and a cathode secured to said conductors means for limiting the direction of movement of the electrons emanating from said cathode, said means surrounding said cathode and having an opening facing said anode, said cathode being located below the upper limit of said means, said means having a rounded upper limit, a cup-shaped control electrode surrounding the mouth of said means and extending an appreciable distance therebelow and shielding means for said presses.

4. An X-ray-circuit electric switch comprising a dielectric envelope having a plurality of presses therein, conductors sealed to said presses, an anode and a cathode electrically connected to said conductors, a cup-shaped means for limiting the direction of electrons emanating at said cathode, said means having an opening in the bottom thereof through which a plurality of said conductors extend, tubular shielding means surrounding one of said presses and extending upwardly to said means, a cup-shaped control electrode across the mouth of said means, the lower limit of the side of said control electrode being located appreciably below the upper limit of said means.

MONTFORD MORRISON.
